No. 774,610.

PATENTED NOV. 8, 1904.

B. S. SMITH,
JACQUARD APPARATUS.
APPLICATION FILED JULY 28, 1903.

NO MODEL.

UNITED STATES PATENT OFFICE.

BENJAMIN SINCLAIR SMITH, OF PAISLEY, SCOTLAND.

JACQUARD APPARATUS.

SPECIFICATION forming part of Letters Patent No. 774,610, dated November 8, 1904.

Application filed July 28, 1903. Serial No. 167,346. (No model.)

To all whom it may concern:

Be it known that I, BENJAMIN SINCLAIR SMITH, a subject of the King of the United Kingdom of Great Britain and Ireland, residing at Stonefield Mills, Paisley, Renfrewshire, Scotland, have invented certain new and useful Improvements in Jacquard Apparatus for Looms, of which the following is a specification.

10 This invention relates to jacquard apparatus for looms, adapted to so manipulate the warps in a loom for weaving pile fabrics that a double fabric is formed comprising two carpets woven face to face in which the pile-warps 15 pass from the upper cloth to the lower cloth, as required by the design, and when not required are floated between the fabrics.

The invention resides more especially in the disposition of the knots relative to the 20 boards and in the arrangement of the boards for lifting, retaining, and lowering the knotted cords connected to the warps, there being provided a stationary board to hold up the lower series of knots, so that the warps 25 connected to the cords are in a floating position, an intermediate lift-board which lifts the upper knots of the selected cords and retains them momentarily in raised position, so as to raise the corresponding warp-threads to 30 the top cloth, to be there woven, and a top lift-board which is lowered to allow the lower knots of the cords not selected to rest on the bottom board, while on the intermediate board descending the selected cords are lowered to 35 lower the warps connected thereto to the bottom cloth and are again lifted to the floating position when the top board is raised.

The invention is illustrated in the accompanying drawings, in which—

40 Figure 1 shows the improved jacquard in diagrammatic form, the details of the apparatus being omitted. Fig. 2 is a diagram showing the lifting-boards and the knotted cords in different positions. Fig. 3 shows a 45 cross-section of the fabric produced in which *a* is the top cloth and *b* is the bottom cloth, while *c* represents the weft-shots in each interwoven with the warp-threads *d*, which threads *d* cross from the top cloth to the bottom cloth, and vice versa, and which threads

when not required for the design float between the cloths, the said warps being severed subsequent to the weaving operation in order to form two carpets, one from the top cloth *a* and the other from the bottom cloth *b*. 55 Fig. 4 is a detail view showing the lifting-boards.

The improved jacquard as regards the framing *e* and the arrangement of and means for operating the card-cylinder *f* and needles *g* is of the usual construction; but it is provided with a top lift-board *h*, to which all the knotted cords *i* of the jacquard are attached, and which board *h* is suspended from and operated by a swinging lever-arm *j*, with a stationary jacquard retaining-board *k* and with an intermediate jacquard lift-board *l*, operated in the usual manner. The top lift-board is shown in up position high enough to so raise the cords *i* that the bottom knots *i'* are all above the stationary board *k*, through which board *k* pass the cords to the usual mails in the warps below. In this position the card on the card-cylinder *f* is pressed into contact with the ends of the needles *g*, so as to act on certain of said needles according to the pattern and to deflect the corresponding cords. The jacquard lift-board *l* is then raised to the position shown in Fig. 1, lifting with it, by the knots *i''*, the cords *i*, that have been selected by the card on the card-cylinder *f*, up to the full-lift, so that the pile-warps attached to said cords are raised to the back of the top cloth *a* in the loom. While the lift-board *l* so retains these warps, the top lift-board *h* is lowered, leaving the cords *i* and knots *i'* not selected by the card on the stationary board *k*, the pile-warps attached to these cords being held floating between the top cloth and the bottom cloth in the manner indicated at Fig. 3. This completes the first cycle of operations. In the second cycle the jacquard lift-board *l* is lowered so that the selected cords, with the knots *i''*, which had raised the selected pile-warps to the top cloth, are lowered, together with the corresponding knots *i''*, as indicated at Fig. 2, to lower these warps down to the bottom cloth, in which they are woven. For this purpose the tails *n* and *m* in the boards *l* and *k*, respectively, run in 100

opposite directions. When this has taken place, the top lift-board *h* is raised so as to bring all the pile-warps to float midway between the two cloths *a* and *b*, and all the knots 5 *i'* are raised above the stationary board *k*, while the knots *i''* are all hanging in position ready for repeating the first cycle of operations, when a fresh card on the cylinder *f* is brought to act on the needles and the lift-board 10 *l* is raised.

The difference between the present jacquard apparatus and those heretofore known is realized partly from the feature that under this invention the warps not selected by the loom 15 float between the top and bottom cloths, both of which are woven as pile carpets figured on both sides. Such a fabric figured on both sides is of quality resembling that of the usual hand-tufted carpet, while in the manufacture, 20 on account of the figure showing on the upper face of the top cloth, the weaver can readily discern whether any of the warp-threads have become accidentally broken. In the manufacture of duplex-pile fabrics as heretofore practiced 25 the warp-threads not selected by the jacquard were taken into either the top or the bottom cloth, so that a figure was formed on one side only of each carpet, and it was difficult or impossible to determine if any of the 30 warp-threads were broken or otherwise.

Having now described my invention, what I claim, and desire to secure by Letters Patent of the United States, is—

In jacquard apparatus of the class set forth, 35 the combination with the usual needles and

cards, of cords arranged to be deflected by said needles, said cords having each two knots *i'*, *i''*, for coöperation with two boards, a stationary bottom board *k* to hold up the lower series of knots *i''* so that the warps connected to the corresponding cords are floating between the two cloths, an intermediate movable lift-board *l* adapted to lift the upper knots of the selected cords through a distance sufficient to raise the corresponding warps into the upper cloth of 45 the fabric and adapted to momentarily retain said selected cords in raised position, a movable top lift-board *h* and an arm *j* for lowering and raising said top board *h*, said board *h* having a downward movement so that the 50 lower knots *i'* of the cords not selected by the jacquard rest on the stationary bottom board *k*, said intermediate board *l* receiving a downward movement sufficient to lower the selected warps into the bottom cloth, and said top 55 board *h* having also an upward movement sufficient to raise all the warps to floating position, whereby a double-pile fabric is produced both of which fabrics are figured upon both sides thereof and the warps not selected float 60 between the two fabrics, substantially as and for the purpose described.

In testimony whereof I have signed my name to this specification in the presence of two subscribing witnesses.

BENJAMIN SINCLAIR SMITH.
